UNITED STATES PATENT OFFICE

150,256

DESIGN FOR A BABY CARRIAGE

Emil Reinhold, Chicago, Ill.

Application January 25, 1947, Serial No. 136,419

Term of patent 7 years

(Cl. D14—14)

To all whom it may concern:

Be it known that I, Emil Reinhold, a citizen of the United States, residing at Chicago, county of Cook, and State of Illinois, have invented a new, original, and ornamental Design for a Baby Carriage, of which the following is a specification, reference being had to the accompanying drawing, forming a part thereof, in which:

Fig. 1 is a rear perspective view of a baby carriage showing my new design as it appears from the left-hand side; and

Fig. 2 is a perspective view from the same side as seen from the front.

I claim:

The ornamental design for a baby carriage, as shown.

EMIL REINHOLD.
